UNITED STATES PATENT OFFICE.

ANTONE E. WOLTER, OF EVERETT, WASHINGTON.

DESIGN FOR AN AUTOMOBILE-RADIATOR ORNAMENT.

53,759.

Specification for Design.

Patented Aug. 26, 1919.

Application filed May 3, 1919. Serial No. 294,587. Term of patent 3½ years.

To all whom it may concern:

Be it known that I, ANTONE E. WOLTER, a citizen of the United States, residing at Everett, in the county of Snohomish and State of Washington, have invented a new, original, and ornamental Design for Automobile-Radiator Ornaments, of which the following is a specification, reference being had to the accompanying drawing, forming part thereof.

Figure 1 is a plan view of an automobile-

radiator ornament showing my new design. Fig. 2 is a side elevational view, and Fig. 3 is a front elevational view of the same.

What I claim, is:

The ornamental design for an automobile-radiator ornament, as shown.

ANTONE E. WOLTER.
